UNITED STATES PATENT OFFICE.

FLORENT PHILIPPE, SR., OF SOUTH CHARLESTON, WEST VIRGINIA.

RAPID TOWEL HANGER.

Application filed August 5, 1922. Serial No. 579,959.

To all whom it may concern:

Be it known that I, FLORENT PHILIPPE, Sr., a citizen of Belgium, and a resident of South Charleston, in the county of Kanawha and State of West Virginia, have invented a new and Improved Rapid Towel Hanger, of which the following is a description.

My invention relates to a towel hanger and more particularly is intended for improvement on a towel hanger forming the subject matter of my Patent No. 1,437,546, patented Dec. 5, 1922.

The general object of the present invention is to provide a towel hanger improved in various particulars with a view to simplify the construction and promote strength as well as to promote precision in the mode of functioning of the device.

Reference is to be had to the accompanying drawings forming a part of this specification, it being understood that the drawings are merely illustrative of practical examples of the invention.

Figure 1 is a face view of a towel hanger embodying my present invention;

Figure 2 is a transverse vertical section taken in the medial plane of the hanger;

Figure 3 is a plan view;

Figure 4 is a face view of my towel hanger illustrating clamping means of somewhat different shape from that shown in Figures 1 to 3;

Figure 5 is a face view illustrating a further change in the shape of the clamping means.

In carrying out my invention in practice a back 10 is provided which in the illustrated example is in the form of a plate having holes to receive screws 11 or equivalent fasteners one of said holes being in a depending extension 12 of the back plate, the lower end 13 of which extension is directed forwardly and preferably upwardly on curved lines. The screws 11 serve to secure the hanger vertically on a wall or other support, a portion of which is indicated conventionally at B.

On the face of the back plate 10 I arrange a clamp designated generally by the numeral 14 formed of a single piece of resilient wire of proper gage or strength. The clamp 14 is made to embody a pair of jaws 15 between which a towel A may be held. In the form shown in Figures 1 to 3 the clamp 14 is formed with a spring coil 16 from

which the material of the clamp extends in opposite directions and is formed into semi-circular portions 16 forming part of the jaws 15, the lower terminals of the semi-circular portions 17 being directed laterally inward toward each other from which terminals the material is carried outwardly to form parallel members 18 and from the outer ends of the members 18 the material is directed upwardly and laterally outward on oblique lines in the form of members 19, the terminals 20 of which are directed outwardly at a more pronounced angle or flare. The forwardly extending members 18 position the face members 19 offset from the front of the back plate 10.

Thus, the semi-circular portions 17, forwardly directed members 18, and oblique members 19 with their terminals 20 constitute the jaws 15 integral with each other. Suitable means is provided to hold the clamp 14 to the back plate 10. In the forms shown in Figures 1 to 3 and those in Figures 4 and 5 and hereinafter referred to, the top portion of the clamp 14 is secured by a curved tongue or clip 21 struck up from the material of the plate 10 and bent over the top of the clamp, which top as shown in Figures 1 to 3 is formed by the coil 16. In addition to the clip 21 retaining members 22 are struck up from the plate 10 and bent into hooked form in front of the curved portions 17 of jaws 15, the free ends being parallel or approximately parallel with said plate 10. The clip 21 positively secures the clamp 14 against displacement while the retaining members 22 constrain the jaws 15 to flex toward or from each other in a plane parallel with the plane of the plate 10.

In the form shown in Figures 1 to 3 I have illustrated a tongue 23 integral with the plate 10 by being struck up from the latter, the lower edge of said tongue 23 curving approximately to conform to the curved portions 17 of the jaws 15 and lying near to the ends of the jaws. With the described arrangement the towel is taken hold of at one corner, conveniently between the thumb and second finger, leaving the corner of the towel projecting above the top of the forefinger. The forefinger is then employed to force the towel downwardly with a sudden movement between the jaws 15, the pressure serving to spread the jaws against the tension of the same.

The downward pressure of the forefinger is continued until the finger passes through the jaw and is arrested by the stop 13, the corner portion of the towel which extends above the forefinger remaining between the jaws to be gripped by the latter when the jaws close, thereby leaving the towel suspended by its corner. The spring tongue 23 prevents the towel from being caught between the jaws of the clamp and the face of the back plate.

In Figure 4 a back plate 110 approximately of the general shape of the back plate 10 is provided and having the same depending extension 12 with turned lip 13. The clamp in Figure 4 designated generally by the numeral 114 is secured by the same elements 21, 22 previously referred to. Sides, 117, instead of being semi-circular have angular bends, the lower ends forming part of the jaws 115, said jaws including the described members 118 offsetting oblique members 119 corresponding with the members 19, the terminals 120 of the said members 119 more pronouncedly flaring.

In Figure 5 the clamp 214 is generally of pear shape, the curved lower ends forming part of the jaws 215 said jaws including the front offset members 219 with terminals 220 directed laterally outward.

It is to be understood that the clamps 114 and 214 are of resilient wire so that the jaws are spring jaws.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. A holder of the class described including a back plate, a clamp disposed on the plate at the front, the lower portion of said clamp forming spring jaws, and a resilient pressed out tongue on the back plate with its lower end in the rear of the jaws to prevent a towel from being entered between the back plate and jaws.

2. As a new article of manufacture, a rapid towel holder comprising a back plate formed with a pressed-out tongue member and a clamp secured to said back plate, said clamp being formed from a unitary piece of wire coiled adjacent its center, the portions of the wire at both sides of the coil being curved to jointly form a ring, said portions extending to a point diametrically opposite said coil and there they are turned forwardly and upwardly in planes diverging from each other and from the longitudinal axis of the back plate to form in the front of the lower end of said tongue member a pair of jaws influenced by said coil to close against each other.

3. In combination with a back plate formed with a hook portion at its lower end and a pressed-out tongue member intermediate its ends, of a wire clamp to constitute a towel holder secured to said plate above said hook portion, said clamp being formed with a pair of springy jaws disposed in the front of the lower end of said pressed-out tongue member, each terminating in an arm diverging laterally outward and upward to provide guiding means for the towel when the same is moved to be placed between the jaws.

FLORENT PHILIPPE, SR.
